(57) **CLAIM**

The ornamental design of a coiled handle for utensils, as
shown and described.

DESCRIPTION

FIG. 1 is a perspective view showing my new coiled handle
for utensils;

FIG. 2 is a front elevational view thereof;

FIG. 3 is a rear elevational view thereof;

FIG. 4 is a left side elevational view thereof, the right side
elevational view thereof being a mirror image of that which
is shown; and,

FIG. 5 is top plan view thereof; the bottom plan view thereof
being a mirror image of that which is shown.

The broken lines are for illustrative purposes only and form
no part of the claimed design.
